UNITED STATES PATENT OFFICE.

THEODORE L. MARVEL, OF TAUNTON, MASSACHUSETTS, ASSIGNOR TO
WILLIAM H. PHILLIPS, OF SAME PLACE.

ELEVATOR.

SPECIFICATION forming part of Letters Patent No. 447,435, dated March 3, 1891.

Application filed October 27, 1890. Serial No. 369,430. (No model.)

To all whom it may concern:

Be it known that I, THEODORE LEONARD MARVEL, of Taunton, in the county of Bristol and State of Massachusetts, have invented 5 an Improved Elevator, of which the following is a specification, reference being had to the accompanying drawings, making a part hereof, in which—

Figure 1 is a side elevation of one form of 10 my elevator. Fig. 2 is a plan, partly in section, on line 2 2 of Figs. 1 and 3. Fig. 3 is a section on line 3 3 of Fig. 2. Figs. 4 and 5 are sectional details showing the chain and its buckets and the supporting-wheels. Figs. 15 6 and 7 are elevations of one of the buckets detached.

Elevators consisting of a slotted frame carrying an endless chain of buckets, mechanism for driving the bucket-chain, mechanism for 20 moving the slotted frame, with its chain of buckets, endwise, and mechanism for tipping it have long been known; and my invention relates to this class of contrivances, and consists, mainly, in mounting the bucket-carrying 25 frame in a tipping frame, the side pieces of which extend across the bucket-carrying frame which moves endwise between these side pieces. This feature of my invention may of course be used with a variety of mechanisms; but other features of my invention 30 relate to improvements in construction by which I produce an elevator which is well adapted for both heavy and light work, which is durable, easily kept in repair, and readily handled.

35 In the drawings, A is a frame (composed of two side pieces a and proper cross-pieces a') supported upon the main shaft B. This frame A receives and guides the frame D by means of guide-blocks a^2 and rollers a^3 . Although, as will be obvious, these blocks and rollers are mere details which may be widely varied, the gist of the matter being that the frame D must be so mounted in the frame A that D may be moved endwise in A, but will 40 tip or tilt as and whenever A is oscillated on shaft B,

As shown in the drawings, frame A is controlled by sprocket-chains a^4 and corresponding wheels a^5 , mounted on shaft a^6 ; but obviously a segmental rack and a pinion are well-known substitutes for chain a^4 and wheels a^5 , and other mechanisms will readily suggest themselves for controlling frame A, which must be oscillated to tip or tilt frame D, and held when frame D is to be kept from tipping or tilting. This feature of my invention—that is, supporting the bracket-carrying frame of an elevator or the like in a stout frame, within which the bucket-carrying frame can be moved endwise, and by which the bucket-carrying frame can be tipped or tilted, as desired—solidifies, strengthens, and simplifies this class of contrivances, and also enables all the mechanisms—namely, those for driving the bucket-chain, for moving the bucket-carrying frame endwise, and for tilting it—to be controlled by the attendant who runs the engine. In fact, elevators and the like with this feature of my invention are practically so vastly superior to all others heretofore known as to constitute a class by themselves. 55 60 65 70 75

In the drawings I have shown the framework F as mounted on wheels f , which rest upon tracks f' , this being for convenience in 80 moving the elevator from place to place; but these matters will obviously vary largely with varying circumstances and uses to which the endless chain of buckets is to be put, as will be clear without further explanation. 85

The engine G supplies power through its shaft g , and the driving-drums g^1 g^2 g^3 g^4 are coupled to shaft g at pleasure by means of suitable mechanism, (not shown,) the drawings being necessarily on a very small scale 90 and too well known to need description. The main shaft B is driven by drums g^1 . Drums g^2 are connected with frame D by the chains or ropes n , passing over pulleys n' , and serve to move frame D endwise. Drums g^3 drive shaft a^6 , by which frame A is oscillated. Drums g^4 connect with ropes r' by means of which frame F can be moved along tracks f' . 95

The buckets d are connected to roller-chains d' , supported by pulleys d^2 , and these 100 chains d' are driven by toothed wheels b on main shaft B.

In operation, for example, taking coal from a collier, the engineer, when the elevator and collier are in proper relation, will first move frame D endwise and upward, (by connecting drums g^2 with shaft g for a moment,) then tilt frame D, (by connecting drums g^3 with shaft g ,) so that when moved endwise its lower end will enter the hold of the collier regulating this downward endwise motion of frame D by a proper brake forming part of the mechanism (not shown) for connecting drums g^2 with shaft g , and having thus brought the lower portion of the bucket-chain into proper relation with the coal he will drive shaft B by connecting drums g' with shaft g , the motion of shaft B and wheels b , fast to it, carrying chains d' and buckets d about the pulleys d^2 . As the coal is elevated and discharged through spout d^3 , the engineer regulates the descent of frame D as may be required.

The main advantages of my improved elevator are that all the mechanisms are readily under the control of the engineer, that the bucket-carrying frame D is held securely by frame

A, through which it moves and by which it is tilted, and that the power is readily applied and so effectively that the waste is much less than in any other contrivance for similar purposes known to me.

What I claim as my invention is—

The improved elevator above described, consisting of a supporting-frame, a main shaft journaled in that frame and having sprocket-wheels thereon, a tilting frame carried by the main shaft, a frame movable endwise through the tilting frame, an endless chain of buckets carried by the endwise-movable frame, said chain engaging with said sprocket-wheels, mechanism for driving main shaft and buckets, mechanism for moving the bucket-carrying frame endwise, and mechanism for controlling the tilting frame, all combined and operating substantially as described.

THEO. L. MARVEL.
